Primary Examiner — Mimosa De(74) *Attorney, Agent, or Firm* — Fitch, Even, Tabin & Flannery LLP(57) **CLAIM**

We claim the ornamental design for a vehicle seat, as shown (and described).

DESCRIPTION

FIG. 1 is a front, top and right side perspective view of a vehicle seat showing my new design;

FIG. 2 is a rear, top and right side perspective view of a vehicle seat showing my new design;

FIG. 3 is a front elevational view thereof;

FIG. 4 is a rear elevational view thereof;

FIG. 5 is a right side elevational view thereof;

FIG. 6 is a left side elevational view thereof;

FIG. 7 is a top plan view thereof;

FIG. 8 is a bottom plan view thereof; and,

FIG. 9 is an end elevation view taken along line 9-9 in FIG. 3 thereof.

The broken lines shown in the drawings represent portions of the vehicle seat that form no part of the claimed design.
